UNITED STATES PATENT OFFICE.

LUIS E. ECKELMANN, OF NEW YORK, N. Y., ASSIGNOR TO PYRENE MANUFACTURING COMPANY, A CORPORATION OF DELAWARE.

FIRE-EXTINGUISHING SOLUTION.

1,421,428.

Specification of Letters Patent. Patented July 4, 1922.

No Drawing.

Application filed October 23, 1919. Serial No. 332,802.

To all whom it may concern:

Be it known that I, LUIS E. ECKELMANN, a citizen of the United States, and resident of the city, county, and State of New York, 5 have invented certain new and useful Improvements in Fire-Extinguishing Solutions, of which the following is a specification.

This invention relates to the production of a new and efficient fire extinguishing 10 agent, being primarily a mixture of one or more polychlorinated hydrocarbons in a form which enables the same to be readily and uniformly mixed or occluded with foam. This foam is in itself the product of the 15 reaction of two water solutions of chemicals and is effective to a certain extent as a fire extinguishing agent for use with certain fires. The object of this invention is to increase the efficiency of the foam and to produce 20 a fire extinguishing agent which will be effective in extinguishing any fire, particularly fires which can not be extinguished by a foam or gas alone.

The invention consists in the novel fire extinguishing mixture or agent and steps for 25 producing the same, constituting the process of combining the polychlorinated hydrocarbon mixture with the foam generating chemicals, obtaining a foam containing the 30 polychlorinated hydrocarbon mixture homogeneously distributed through it at the time of its generation and projection upon the fire. The invention also consists, in part, 35 of the introduction of a mixture of one or more fire extinguishing polychlorinated hydrocarbons into a solution of water soluble chemicals used to produce foam.

Owing to the fact that the mixture of 40 polychlorinated hydrocarbons used is insoluble in water, and also in water solutions of sodium bicarbonate and aluminium sulphate as used in the foam type of fire extinguisher, it is evident that the polychlorinated hydrocarbon mixture could not be 45 introduced into either of the two solutions and be dissolved or held in homogeneous suspension, but would separate out into distinct layers or portions of the water solution and the polychlorinated hydrocarbon mixture. This condition would impair the 50 successful action of the extinguisher in so far as the polychlorinated hydrocarbon content and distribution of same in the foam was concerned, as the polychlorinated hydro- 55 carbon being so held could not mix with the

reacting solutions and be expelled through the nozzle in the quantities or manner required to act efficiently in extinguishing the fire. Furthermore, it was found that a satisfactory mixture of the polychlorinated 60 hydrocarbon and the aluminium sulphate solution could not be obtained even when this last solution (selected because of its great solubility in water) was concentrated to a density and specific gravity approaching 65 that of the polychlorinated hydrocarbon mixture.

It is a known fact that in many instances liquids mutually insoluble can be mixed, and will continue more or less so, if the two 70 components be of the same density and specific gravity. The difficulty of obtaining a stable mixture of the polychlorinated hydrocarbon mixture and the concentrated solution of the aluminium sulphate is due 75 to the fact that the aluminium sulphate solution can not be brought up to a sufficiently high specific gravity to be equal to that of the polychlorinated hydrocarbon mixture and still remain in solution. 80

With the above difficulty to overcome in view, I first produce the polychlorinated hydrocarbon mixture in an emulsified form. I have found that if the polychlorinated hydrocarbon mixture is emulsified, by mixture 85 and agitation with solutions of saponin, gum arabic, soaps, etc., it is then possible to mix this emulsion and a water solution containing aluminium sulphate without enough separation occurring to render the 90 action of the foam generating chemicals incomplete, in so far as the occlusion or retention of the emulsion throughout the foam is concerned.

Another important point to be noted is the 95 fact that an emulsion made from carbon tetrachloride alone will not be suitable for combination with the aluminium sulphate solution used in the foam extinguisher. Emulsions made from carbon tetrachloride 100 alone separate out more easily and are not held in the water solution of aluminium sulphate quite as well as those made from mixtures of carbon tetrachloride with other non-inflammable polychlorinated hydrocarbons of lower specific gravity. Consequently, the emulsion used in producing the fire extinguishing agent will preferably be compounded from mixtures of carbon tetrachloride with other polychlorinated hydro- 105 110

carbons or substances to give the most satisfactory results, which constitutes another important feature of the invention.

In carrying out my invention I proceed 5 as follows:

I charge the extinguisher, which may be of the type ordinarily used for producing foam alone, containing two compartments of different size, with the two foam generating solutions, which may be composed of sodium bicarbonate and aluminium sulphate or any suitable solutions for this purpose. It is preferable to charge the larger compartment of the extinguisher with the solution 10 of sodium bicarbonate. The aluminium sulphate solution, concentrated to a density as near equal to that of the emulsion as possible, is mixed with the emulsion, preferably in the proportion of three parts of emulsion to two parts of aluminium sulphate solution and put into the inner compartment. At this point, mention must be made of the fact that I have found I can also mix the emulsion with powdered aluminium sulphate, 15 powdered bicarbonate, or any other of the constituents of the foam generating chemicals and not depart from the spirit of the invention.

Upon discharging the extinguisher in the usual manner, by reversing the position of the same and causing the contents of the two compartments to mix, the aluminium sulphate and sodium bicarbonate solutions will react, producing a foam which will 20 carry the emulsion equally and homogeneously distributed through it at all times during the period of discharge. The foam will be expelled through the nozzle of the extinguisher in the usual manner on the fire, covering same with a heavy blanket of 25 foam and smothering the flames. This smothering action of foam alone is not sufficient to effectively extinguish all fires, however, and the new combination and invention herein described will not only retain the smothering function of the foam, but, in addition, will carry a polychlorinated hydrocarbon base, the extinguishing efficiency of which is well recognized. Should 30 the foam blanket be dried and consequently ruptured by the heat of the fire, which is very liable to occur in hot fires, such as oil tank fires, etc., thereby exposing portions of the burning liquid to the air and permitting or increasing further combustion, the polychlorinated hydrocarbon mixture held in the emulsion and now evenly distributed through the foam blanket will be vaporized, forming a heavy, non-combustion-supporting 35 gas blanket which will effectively extinguish any portions of the fire unacted upon by the foam.

The production of a fire extinguishing medium possessing the added advantage of 40 extinguishing fluid with a carbon tetrachloride base and foam would naturally be an advantage in this field and give a product of increased efficiency.

In order to obtain a mixture of this sort certain difficulties had to be overcome as the tetrachloride base mixture had to be put in such form as to render it readily miscible with the foam generating chemicals which are water soluble.

Previous experiments have shown that the tetrachloride mixture could not be held in combination homogeneously if in its original form, consequently attempts were made to produce a uniform suspension of the tetrachloride mixture with the aqueous solutions of foam generating chemicals. Owing to the fact that uniform mixtures of liquids insoluble in one another will be more complete if the relative specific gravities of the two are the same or similar, the aluminium sulphate solution was chosen to mix with tetrachloride mixture. No success was met with, as the tetrachloride base mixture separated out in every case. The next step was to find some method or means by which the tetrachloride base mixture could be put into such form as to render it miscible with water solutions, bearing in mind that oil (insoluble in water) can be made to mix with same if made into an emulsion. The same was tried using the tetrachloride base mixture in place of the oil.

In order to produce a stable emulsion of carbon tetrachloride different emulsifying agents, such as saponin, gumarabic, soap, etc., were used. It was then found that with 100 tetrachloride alone the production of an emulsion was not very easy, also that it had a tendency to separate out into its components on standing, this being doubtless due to the high specific gravity of the tetrachloride (1.6). Consequently, the next step was to decrease the specific gravity of the tetrachloride base mixture, by adding various non-inflammable polychlorinated hydrocarbons of lesser densities. Emulsions made 105 with these mixtures are very permanent, not separating out easily. It was found that the addition of light oils in amounts of one to three per cent, further improved the permanency and fluidity of the emulsion.

After obtaining an emulsion which could be kept indefinitely without separation, containing carbon tetrachloride and other polychlorinated hydrocarbons, tests were made to determine the best method of combining 110 this emulsion with the foam generating solutions for use in the standard type of extinguisher. The emulsion of polychlorinated hydrocarbons was mixed with a solution containing aluminium sulphate which could be concentrated to a density approaching that of the emulsion. By mixing the two constituents in this manner the tendency to separate was retarded to a great degree. It must be noted that even though the emul- 115

120 125 130

sion will settle to the bottom of the container holding the mixture, the separation in this case is not distinct and sharp as when aluminium sulphate solution and tetrachloride 5 are mixed but can be considered as an agglomeration of the emulsified particles in the sulphate solution itself. Practically any proportions of emulsion and aluminium sulphate solution can be used, depending 10 only upon the size of container, amounts of foam and expelling pressure desired.

Upon discharging the extinguisher in the usual manner the sodium bicarbonate and aluminium sulphate containing the emulsion 15 will react, producing the foam and expelling the same through the nozzle. The foam will carry with it the tetrachloride mixture emulsion homogeneously distributed through it. The quantity of emulsion 20 in the foam will be proportionally equivalent to the amount originally added.

When the tetrachloride mixture foam is projected upon a fire, a foam blanket will be formed. The heat of the fire which might 25 dry portions of this blanket and rupture same, will expose the burning liquid to the air and renew combustion (this will be the case in extinguishing an oil fire in a tank or vat, where the entire surface is burning). 30 At this point the tetrachloride solution already in the foam, vaporized by the heat of the fire, will form a gas blanket over the uncovered portions, effectively extinguishing the fire.

35 What I claim is:—

1. A fire extinguishing mixture comprising the combination of a non-aqueous fire extinguishing liquid with an ingredient adapted to increase the surface tension of 40 the liquid and constituents adapted to generate a tenacious fire extinguishing foam.

2. A fire extinguishing mixture comprising the combination of a non-aqueous fire extinguishing liquid with an ingredient 45 adapted to increase the surface tension of the liquid and a reacting salt solution adapted to generate a tenacious foam.

3. A fire extinguishing mixture comprising the combination of a non-aqueous fire 50 extinguishing liquid with a sodium bicarbonate solution adapted to generate a tenacious foam.

4. A fire extinguishing mixture comprising the combination of a non-aqueous fire 55 extinguishing liquid with a sodium bicarbonate and aluminium sulphate solution adapted to generate a tenacious foam.

5. A fire extinguishing mixture comprising the combination of a non-aqueous fire 60 extinguishing liquid with concentrated solutions of sodium bicarbonate and aluminium sulphate adapted to generate a foam.

6. A fire extinguishing agent comprising a mixture of a polychlorinated hydrocarbon 65 with a reacting salt solution adapted to

generate a tenacious fire extinguishing foam.

7. A fire extinguishing agent comprising a mixture of carbon tetrachloride and another polychlorinated hydrocarbon with a reacting salt solution adapted to generate a 70 fire extinguishing foam.

8. A fire extinguishing agent comprising a mixture of carbon tetrachloride with a concentrated solution of aluminium sulphate adapted to generate a fire extinguishing foam. 75

9. A fire extinguishing mixture comprising the combination of an emulsion of a polychlorinated hydrocarbon with constituents adapted to generate a fire extinguishing foam. 80

10. A fire extinguishing agent comprising a mixture of an emulsion of carbon tetrachloride and another polychlorinated hydrocarbon with a constituent adapted to 85 generate a fire extinguishing foam.

11. A fire extinguishing agent comprising a mixture of an emulsion of carbon tetrachloride and another polychlorinated hydrocarbon with a concentrated solution of aluminium sulphate adapted to generate a fire extinguishing foam. 90

12. A fire extinguishing agent comprising a mixture of an emulsion of carbon tetrachloride and another polychlorinated hydrocarbon and oil with a reacting salt solution adapted to generate a fire extinguishing foam. 95

13. A fire extinguishing agent comprising a mixture of an emulsion of carbon tetrachloride with other polychlorinated hydrocarbons of less specific gravity and oils, with a concentrated solution of aluminium sulphate adapted to generate a fire extinguishing foam. 100 105

14. The process of producing a fire extinguishing mixture which comprises generating a tenacious foam mixed with a non-aqueous fire extinguishing liquid.

15. The process of producing a fire extinguishing agent which comprises generating a tenacious foam mixed with a polychlorinated hydrocarbon. 110

16. The process of producing a fire extinguishing agent which comprises generating a foam mixed with carbon tetrachloride and another polychlorinated hydrocarbon. 115

17. The process of producing a fire extinguishing mixture which comprises producing an emulsion of a polychlorinated hydrocarbon, generating a fire extinguishing foam in contact with said emulsion. 120

18. The process of producing a fire extinguishing agent which comprises in producing an emulsion of carbon tetrachloride and another polychlorinated hydrocarbon, generating a fire extinguishing foam in contact with said emulsion. 125

19. The process of producing a fire extinguishing agent which consists in pro- 130

- ducing an emulsion of carbon tetrachloride and another polychlorinated hydrocarbon and oil, generating a fire extinguishing foam in contact with said emulsion.
5. 20. The process of producing a fire extinguishing agent which consists in producing an emulsion of carbon tetrachloride with other polychlorinated hydrocarbons of less specific gravity and oils, generating a foam 10 with a concentrated solution of aluminium sulphate, in contact with said emulsion.
21. A fire extinguishing agent comprising two constituents producing a foam in reaction, and a polychlorinated hydrocarbon 15 mixture having substantially the same specific gravity as one of said foam producing constituents and mixed therewith.
22. The process of producing a fire extinguishing agent which consists in forming 20 an emulsion of polychlorinated hydrocarbons having substantially the same specific gravity as one of two foam producing constituents, mixing said foam producing constituent and emulsion, and producing a foam 25 carrying said emulsion by the reaction of said last named mixture and a second foam producing constituent.
23. The process of producing a fire extinguishing agent which consists in forming 30 a mixture of carbon tetrachloride and other polychlorinated hydrocarbons of less specific gravity to form a mixture having substantially the same specific gravity as one of two foam producing constituents, forming an emulsion of said mixture, mixing said foam producing constituent and emulsion, and producing a foam carrying said emulsion by the reaction of said last named mixture and a second foam producing constituent.
24. A fire extinguishing agent containing a mixture of polychlorinated hydrocarbons of different specific gravities, and foam producing ingredients.
25. A fire extinguishing agent containing a mixture of an emulsion of polychlorinated hydrocarbons of different specific gravities, and foam producing ingredients.
26. A fire extinguishing agent containing a mixture of a saturated polychlorinated hydrocarbon and ingredients adapted to produce a tenacious foam.
27. A fire extinguishing agent containing a mixture of a plurality of different polychlorinated hydrocarbons and ingredients adapted to produce a tenacious foam.

Signed at the city, county and State of New York, this 8 day of Oct. 1919.

LUIS E. ECKELMANN.
